(57) **CLAIM**

The ornamental design for a milk frother, as shown and described.

DESCRIPTION

FIG. 1 is a front, right, top, perspective view of a milk frother, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view of the enlarged scale thereof;

FIG. 8 is a bottom plan view of the enlarged scale thereof;

FIG. 9 is an enlarged view of detail 9 in FIG. 2;

FIG. 10 is an enlarged view of detail 10 in FIG. 4;

FIG. 11 is an enlarged view of detail 11 in FIG. 5; and,
FIG. 12 is a front, right, top reference view of the milk frother, indicating the usage environment.

The dashed broken lines illustrating the stand in FIG. 12 are for environmental purposes only and form no part of the claimed design.

The other dashed broken lines illustrate portions of the milk frother which form no part of the claimed design.

The dash-dot-dash broken lines are for notating enlarged views and form no part of the claimed design.

1 Claim, 12 Drawing Sheets
